VALVE

Frederick F. Rike, Dayton, Ohio, assignor to
 Buckeye Iron and Brass Works, Dayton, Ohio,
 a corporation of Ohio

Application September 8, 1931. Serial No. 561,638

6 Claims. (Cl. 251—165)

This invention relates to improvements in valves, and has for its object to provide a valve mechanism adapted to be used in connection with truck tanks, in which there is a valve casing containing a passageway therein for the discharge of liquid from a tank, and in which there is a valve guided by means of integral ribs on the casing around the passageway.

It is also an object of this invention to provide, in connection with a valve mechanism, a casing in which there is a substantially straight passageway with an inlet leading thereto. In this passageway is a valve for closing the passageway, which valve is held closed by means of a spring pressing against the valve through the agency of a cap for closing one end of the passageway.

It is also an object of this invention to provide, in connection with a valve casing having a passageway therein, means for closing the outlet end of said passageway so that a double closure is provided to prevent the unnecessary and wasteful escape of liquid through the valve casing. This cap cooperates with a valve normally used for opening and closing the passageway.

These and other advantages will appear from the following description taken in connection with the drawings.

Referring to the drawings:

Figure 1 is a side elevation of the faucet mechanism with a part thereof shown in section. In this view the valve is shown about one-half open.

Figure 2 is a view showing part of the valve mechanism in section. In this view the valve is shown only slightly open for the discharge of a small amount of liquid.

Figure 3 is a section on the line 3—3 of Figure 1.

Figure 4 is a section through the valve mechanism and the handle for operating the valve.

Figure 5 is a side elevation of the operating handle with one end thereof slightly broken away.

Figure 6 is a section through the outlet end of the casing showing the means for locking the cap thereon.

Figure 7 is a vertical, longitudinal section through the valve mechanism showing the valve seated and the cap in position for closing the discharge end of the passageway through the valve casing.

Figure 8 is a view similar to Figure 7 but with the lock cap removed.

The present invention relates to truck tank faucets and consists of a casing 1, which has a substantially straight passageway therethrough with which a lateral inlet 2 connects. The inlet

part of the casing is adapted to be attached to some tube or pipe 3 of the tank for the discharge of liquid such as gasoline from the tank to a receiving container. This receiving container may be an underground tank, or any other vessel into which gasoline or a similar fluid is to be discharged.

One end of the passageway constitutes an outlet 4, while the other end constitutes an extension 5 into which the inlet enters. Intermediate the ends of the passageway the casing is provided with a valve seat 6 extending around the passageway. The passageway is closed by means of a valve mechanism consisting of a valve plate 7, which has extending therefrom a valve stem 8. For the purpose of guiding the valve plate in its movement to and from the valve seat the interior of the casing is provided with a plurality of guide ribs 7'. In the present instance these ribs are formed integral with the casing.

In order to close one end of the passageway there is provided a cap 9 which fits over the open end of the extension 5. This cap is threaded onto the extension and has extending inwardly from the center thereof a projection 10 with a socket 11 therein to receive the stem 8 of the valve. Between the cap and the valve and around the stem and the projection is a spring 12, normally acting to hold the valve in closed position on the valve seat. Around the valve stem adjacent the valve plate is a shoulder 13, around which one end of the spring 12 fits.

On the side of the valve opposite the stem is an extension 14 which has threaded thereon a nut 15. This nut is threaded against a plate or disc 16, which bears against the valve disc 17. The valve disc 17 is between the valve plate 7 and the disc 16, and is held between these two in a tight condition by means of the nut 15.

Located on the front side of the valve casing and extending to the right therefrom, as shown in Figure 3, is a shaft 18. This shaft may extend from the left side of the casing, and when the shaft is thus positioned a housing or bearing is provided. For supporting this shaft there is provided on the side of the casing a housing or bearing. Extending from the shaft within the casing is an arm 19, which has on its inner end remote from the shaft a head 20 for engaging the extension 14 on the valve.

Whenever the shaft is rotated in the proper direction the head will engage the extension 14 and lift the valve from its seat so that the fluid may pass around the valve and through the passageway. In order to form a liquid-tight inclo-

110

sure between the shaft 18 and the casing there is provided a gland 21, which has between it and the casing packing for containing a lubricant or means for preventing the leaking of the liquid 5 around the shaft. The outer end of the shaft 18 is square, as indicated by the numeral 22.

This square end is adapted to receive a socket member 23, which has a square hole therein to receive the square end of the shaft. To this 10 socket member is pivoted a handle 24. This handle has a yoke 25 adjacent one end, into which the socket member extends. The socket member is held in the yoke by means of a pin 26, which permits the free swinging movement of the 15 socket member within the yoke.

The end 27 of the handle adjacent the yoke is quadrant in formation and has on the outer end thereof a plurality of seats 28 and 28^a. These 20 seats are arranged symmetrically on opposite sides of the central line of the handle, seats 28 on one side and seats 28^a on the other. As shown in Figure 5, there are three of these seats on each 25 side of the central line. These seats are arranged in pairs, the seats of each pair being in vertical alignment with each other, but no pairs of seats are in vertical alignment. In other words, the seats on each side of the vertical center of the handle are arranged in step formation.

When the handle is on the righthand side of 30 the casing for operating the shaft for opening or closing the valve, it may be locked in any particular position by causing one of the seats 28 to engage a stud 29 suitably located on the casing. But when the handle is on the lefthand side of 35 the casing it may be locked in position by causing the stud 29 to engage any one of the seats 28^a, since the handle has been turned over and the same movements are used for operating the handle.

When the lever is used with the shaft and 40 stud, as shown in Figure 4, the seats 28 on one side of the longitudinal center of the handle are used for locking the handle in a definite position for holding the valve open. When the handle is located on the side opposite the one on which it 45 is located in Figure 4, the seats 28^a on the other side of the handle are used for locking the valve open.

To one side of the discharge or outlet end of 50 the passageway is a projection 30, such as is usually found in connection with valve structures of this kind. There is also suitably located at the outlet end of the casing a lock lug 31. For insertion in the outlet end of the casing 55 there is provided a threaded nipple 32. The nipple is shown inserted in the casing in Figures 7 and 8. Both ends of the nipple are threaded and either may be inserted into the outlet part of the passageway. When the nipple is thus inserted in the casing there is provided a cap 33 60 for closing the outlet passageway by threading the cap on the other threaded end of the nipple. Extending around the periphery of the cap in a spider rim 34.

In order to lock the cap on the nipple a padlock 65 may be used, as shown in Figure 6. In this figure the padlock incloses the rim of the spider and a part of the lug 31. A hole is provided in the lug 31 for receiving the locking member of the padlock. By use of the padlock the cap can 70 not be rotated to remove it from the nipple.

The purpose of this cap 33 is to prevent stealing 75 of gasoline and to form a secure closure for the discharge end of the valve casing. After

the gasoline or other fluid has been discharged the valve is closed. If through some cause, wear or otherwise, the valve may not properly seat and a slight leakage takes place around the valve, in order to prevent any loss due to such leakage 80 the cap 33 is provided.

The plurality of seats on the quadrant end of the handle is provided in order to effect a plurality of adjustments of the valve for the discharge of gasoline or other fluid from the tank. 85 When a large quantity of fluid is to be discharged the valve may be opened and the stud 29 seated in the seat most remote from the longitudinal center of the handle. In the event a small amount of liquid is to be discharged, such 90 as five or ten gallons, the handle 24 is adjusted so that the seat 28 adjacent the longitudinal center of the handle receives the stud 29. Whenever the handle has been properly adjusted with the stud 29 in the desired seat, the discharge of fluid 95 can take place without any trouble or care on the part of the operator.

I desire to comprehend within my invention such modifications as may be embraced within my claims and the scope of my invention.

Having thus fully described my invention, what I claim as new and desire to secure by Letters Patent, is:

1. In a truck tank faucet, a casing having a 105 passageway therein, a valve adapted to close said passageway, means to open said valve including a shaft, a socket member adapted to removably engage the shaft, a handle pivoted to said socket member, and cooperating means on the casing and the handle to lock the handle in a plurality 110 of positions whereby the valve may be held in different positions, said cooperating means including a lug on the casing and a plurality of lug seats on the handle.

2. In a truck tank faucet, a casing having a 115 passageway therein, means to close said passageway, means on said casing to operate the first-named means to open the passageway, a handle 120 adapted to engage said last-named means, said handle having a quadrant-shaped end with a plurality of seats therein, and means on the side of the casing to engage the seats to hold the handle and the first-named means in different positions.

3. In a truck tank faucet, a casing having a 125 passageway therein, a valve to close said passageway, means on said casing to operate said valve, a socket member adapted to engage said means to operate the valve, a handle pivoted to said socket member, said handle having a quadrant-shaped end with a plurality of seats on each side of the center line of the handle, and means on the side of the casing to be engaged by the seats to hold the handle and the valve in different positions.

4. In a truck tank faucet, a casing having a 140 passageway therein, a valve to close said passageway, means on the side of said casing to operate said valve, a socket member adapted to engage said means to operate the valve, a handle pivoted to said socket member, said handle having a quadrant-shaped end with a plurality of seats on each side of the center line of the handle, and a stud on the side of the casing to be engaged by the seats to hold the handle and the valve in different positions.

5. In a truck tank faucet, a casing having a 145 passageway therein, a valve to close said passageway, one end of said passageway constituting 150

an outlet, a detachable cap adapted to close the outlet, said cap having a peripheral spider member thereon, and means engaging the spider member to lock the cap on the outlet.

5 6. In a truck tank faucet, a casing having a passageway therein, a valve to close said passageway, one end of said passageway constituting

an outlet, a nipple threaded in said outlet, a cap threaded on said nipple to close the outlet, and means engaging the casing and the cap to hold the cap on the nipple, said means including a spider rim on the cap and a lug on the casing. 80
